UNITED STATES PATENT OFFICE

149,196

DESIGN FOR A FAUCET UNIT

John M. Little and Amy L. Thomssen,
Toledo, Ohio

Application October 9, 1946, Serial No. 133,854

Term of patent 14 years

(Cl. D91—3)

To all whom it may concern:

Be it known that we, John M. Little and Amy L. Thomssen, both citizens of the United States, and both residing at Toledo, Lucas County, State of Ohio, have invented a new, original, and ornamental Design for Faucet Unit, of which the following is a specification, reference being had to the accompanying drawing, forming a part thereof, in which—

In the drawing:

Figure 1 is a top view of a faucet unit, showing our new and ornamental design;

Figure 2 is a side view of the design; and

Figure 3 is a front view of the design.

We claim:

The ornamental design for a faucet unit, substantially as shown.

JOHN M. LITTLE.
AMY L. THOMSSEN.
